DESIGN FOR A COMBINED TOBACCO HUMIDOR AND PIPE RACK OR SIMILAR ARTICLE

Max Stern, New York, N. Y.

Application July 16, 1937, Serial No. 70,485

Term of patent 3½ years

To all whom it may concern:

Be it known that I, Max Stern, a citizen of the United States and resident of New York, in the county and State of New York, have invented a new, original, and ornamental Design for a Combined Tobacco Humidor and Pipe Rack or Similar Article, of which the following is a specification, reference being had to the accompanying drawing, forming part thereof.

In the drawing:

Fig. 1 is a front elevation of a combined tobacco humidor and pipe rack or similar article, showing my new design.

Fig. 2 is a top plan view thereof.

Fig. 3 is a side elevation of the same.

I claim:

The ornamental design for a combined tobacco humidor and pipe rack or similar article substantially as shown.

MAX STERN.
